[57] CLAIM

The ornamental design for a towel rack, as shown and described.

DESCRIPTION

FIG. 1 is a front elevational view of a towel rack, showing my new design;

FIG. 2 is a left side elevational view thereof, the right side being a mirror image of that shown;

FIG. 3 is a rear elevational view thereof;

FIG. 4 is a top plan view thereof;

FIG. 5 is a bottom plan thereof;

FIG. 6 is a vertical cross-sectional view thereof, taken in the direction of line 6—6 of FIG. 1; and

FIG. 7 is a perspective view thereof.
